(57) **CLAIM**

The ornamental design for a cosmetic collection, as shown and described.

DESCRIPTION

FIG. 1 is a perspective front view of another embodiment of a cosmetic collection, embodying the new design; FIG. 2 is a front view of the design shown in FIG. 1; FIG. 3 is a back view of the design shown in FIG. 1; FIG. 4 is a left side view of the design shown in FIG. 1; FIG. 5 is a right side view of the design shown in FIG. 1; FIG. 6 is a bottom view of the design shown in FIG. 1; and FIG. 7 is a top view of the design shown in FIG. 1. The two different areas (i.e., lighter and heavier densities) of diagonal line shading in these figures represent two different shades of the color green.

FIG. 8 is a perspective front view of another embodiment of a cosmetic collection, embodying the new design; FIG. 9 is a front view of the design shown in FIG. 8; FIG. 10 is a back view of the design shown in FIG. 8; FIG. 11 is a left side view of the design shown in FIG. 8; FIG. 12 is a right side view of the design shown in FIG. 8; FIG. 13 is a bottom view of the design shown in FIG. 8; and, FIG. 14 is a top view of the design shown in FIG. 8.

The two different areas (i.e., lighter and heavier densities) of diagonal line shading in these figures represent two different shades of the color green.

The broken lines shown in the figures illustrate environmental features and form no part of the claimed design.
